UNITED STATES PATENT OFFICE.

HARRY PRICE, OF HANDSWORTH, ENGLAND.

SINGLE-TRIGGER MECHANISM FOR DOUBLE-BARREL GUNS.

No. 802,314.

Specification of Letters Patent.

Patented Oct. 17, 1905.

Application filed June 1, 1904. Serial No. 210,727.

To all whom it may concern:

Be it known that I, HARRY PRICE, a subject of the King of Great Britain, residing at 38 Linwood road, Handsworth, in the county of 5 Stafford, England, have invented certain new and useful Improvements in Single-Trigger Mechanism for Double-Barrel Guns, of which the following is a specification.

My invention relates to improvements in 10 single-trigger mechanism for double-barrel guns, and has for its object improved means whereby the action of opening and closing of the breech of the gun places the trigger mechanism in the position to fire the right barrel; 15 also, improved means whereby upon the fall of either of the hammers the trigger mechanism is placed in position for firing the other barrel; also, improved means whereby the accidental or involuntary firing of the remaining barrel during the recoil from the first 20 firing is prevented; also, improved combination of these last-mentioned means with the safety mechanism. These my improved means apply to "side" as well as what are known 25 as "hammerless" gun-locks.

I illustrate this my invention in the accompanying drawings, upon which are figures and numbers of reference, similar numbers referring throughout the several views to the 30 same thing or part, and in which—

Figure 1 shows a part-sectional side view of such parts of an interior gun-lock mechanism as may be necessary to explain this my invention. Fig. 2 is a part-sectional plan 35 view of the mechanism, showing the position of the parts as seen when ready for firing the right-hand barrel. Fig. 3 is an enlarged side view, and Fig. 4 a plan view, of certain important parts of this my invention, such as 40 the slide which is operated by the falling of the hammer in order to move the switch from the right-hand barrel to the left. Fig. 5 is a detached side view of the breech-locking bolt. Fig. 6 is a detail view of the left-hand slide, which is operated by the fall of the hammer. Fig. 7 is a detail view of the 45 right-hand slide, which is operated by the falling of the hammer. Fig. 8 is a side view, and Fig. 9 a plan view in detail, of the switch-arm. Fig. 10 is a sectional plan view of a 50 portion of the switch-arm and a V-spring which acts thereon. Fig. 11 is a part-sectional view showing the trigger in connection with the recoil mechanism. Fig. 12 shows 55 the position of the switch-arm during the recoil action. Fig. 13 is a view of the parts of

an outside gun-lock, showing this my invention as applied to it.

Only such parts of the gun and its mechanism are shown as may be necessary to explain this my invention, in which—

16 represents the breech-block, in which are carried the usual parts—such as, the right-hand hammer 17 and left-hand hammer 17^a, its spring 18, breech-bolt lever 19, trigger 20, 60 which is pivoted at 21 to the trigger-block 22. 23 is a switch-arm having a vertical stem 24, upon which is shaped a V edge 25. This switch-arm is pivoted at 26 to the trigger. 27 is a spring secured at 28 to the post 29, which 65 forms part of the trigger. This spring is furnished with a V-shaped part at 30, which acts upon the V-shaped part 25 of the switch-arm in such a manner that when the said arm is pushed slightly to the one or the other side 70 from the position shown in Fig. 10 the said spring acts upon the sides of the part 25 and completes its movement. 31 is a slide which is carried upon the right-hand side of the trigger-block 22, and 32 is a slide carried upon 75 the left-hand side of the trigger-block 22. At the forward end of the slide 31 is formed the incline surface 33, and the rear end 34 of the said slide is made to operate against the part 35 of the switch-arm when the right-hand 80 hammer has fallen by the raising of the trigger and while the trigger is in its raised position. Upon the slide 32 is also an incline surface 36, which is operated upon by the left-hand hammer, the said slide having also the 85 rear part 37, which, upon the firing of the left-hand barrel, pushes against the part 38 of the arm 23, so as to turn it toward the right-hand sear-lever 39. 40 is the left-hand sear-lever. Upon each of the slides 31 and 32 are 90 similar inwardly-projecting pegs 41, against the rear side of which presses the spring 42, which is secured at 43 to the trigger-block 22, so as always to press the said slides forward 95 toward the hammer. Upon the hammers 17 100 17^a are provided similar inwardly-projecting pegs 44, which act upon the surfaces 33 and 36 of the aforesaid two slides. 45 is the breech-locking bolt which is operated in the usual manner by the lever 19 and its crank 46. 105 These parts are the usual well-known parts, and therefore are not further illustrated. Upon the bolt 45 is the projection 47, which rests against the peg 41 upon the slide 32, so that when the lever 19 is turned to the one side 110 in order to unlock the breech the bolt 45 in its movement carries rearward the part 47

against the peg 41 upon the slide 32, and thus forces the said slide rearward, which in its turn forces the part 37 against the part 38, so as to partially rotate the stem 24 until the edge 5 at 25 has just passed the edge 30 of the spring 27, when the said spring completes the part rotative movement of the arm 23 until the part 48 is carried beneath the sear-lever 39—that is, ready for firing the right barrel. Hence when 10 the trigger is raised the sear-lever 39 is raised so as to release the hammer 17 from bent, and the right-hand barrel is fired. While the trigger is thus held in its raised position, the movement of the said hammer takes place, 15 and with such movement the peg 44 of the right-hand hammer moves upon the incline surface 33, which causes the slide 31 to move rearward, and by means of the part 34 acting against the part 35 of the arm 23 the said arm 20 is moved over to the left for firing the left-hand barrel. (See Fig. 4.) The left-hand barrel then having been fired the gun is opened for recharging, in the act of which the arm 23 is pushed back to beneath the right-hand 25 sear 39 by means of the bolt 45 in the manner already described.

As is well known, in single-trigger mechanism there is danger of involuntarily firing the remaining barrel under the recoil action 30 due to firing the first barrel, and my improved means obviate this difficulty as follows: Upon the trigger-plate 50 is an upright post 51, upon which is placed the sliding block 52, the said post 51 slidably fitting in 35 the slot-hole 53, formed in the said block 52. Between the end of the slot-hole 53 and the post 51 is placed a light spring 54, which tends always to keep the block 52 in its rearward position. At the forward end of the 40 block is the projection 55, which coacts with the projection 56, formed upon the trigger 20. Now when the trigger is raised (see Fig. 11) in order to fire either of the barrels the said firing causes the gun to recoil, and in its 45 sudden movement the projection 56 upon the trigger is carried over the projection 55, due to the inertia of the block 52. It will also be noticed, as before described, that while the trigger is in this raised position the switch- 50 arm 23 is moved over toward the opposite sear, but inasmuch as the trigger is thus kept in its raised position during this involuntary action the said arm 23 would merely rest against the end of the sear-lever, (see Fig. 12,) and thus no 55 action upon the said sear-lever can take place until the danger from recoil has subsided and the block 52 brought rearward by its spring 54, when the trigger will be lowered, and immediately this latter takes place the part 48 or 60 the part 49 of the arm 23 is then free to move beneath the sear-lever ready for firing the opposite barrel.

The safety mechanism is constructed as follows: 57 is the usual safety-slide, which is 5 moved rearward by the crank 46 upon the

turning-lever 19, and in its rearward movement turns the lever 58 upon its pivot 59, and in so doing the block 52 is moved forward by the end 60 of the lever 58, so that the projection 55 is now pushed over the projection 56, 70 which is formed upon the trigger 20, and thus prevents the possibility of the trigger being raised until the usual thumb-piece 61 has been pushed forward so as to permit the return movement of the block 52—that is, to place 75 it out of safety.

If it is desired to fire the left barrel before firing the right, the switch-arm 23 is moved to the left by means of the sliding push-piece 62, to which is attached the plate 63, upon 80 which is carried the upstanding piece 64, which in its movement presses against a part 35 of the arm 23, and thereby turns it over to the left sear.

Referring now to Fig. 13, it will be seen 85 that this represents what is known as a "side-lock action" and is merely illustrated to show that the peg 44 is essentially the same as those carried upon the hammers already described and in which such peg operates upon the incline surface 65 of the slide 66, the latter being the equivalent of either of the previously-described slides 31 and 32 and in a similar manner operating the switch-arm 23. The mounting of the parts 23 and 66 and the various other parts (not shown) will be to all intents and purposes carried out in the manner shown and described in relation to the previous figures.

What I claim as my invention, and desire 90 to secure by Letters Patent, is—

1. In a single-trigger mechanism for double-barrel guns, the combination of the hammers having a projection 44, a trigger-block having slides thereon provided with inclined 105 edge surfaces with which the projections 44 operate, a switch-arm pivotally carried by the trigger, the rear ends of the slides being adapted to move the switch-arm about its center, and sear-levers with which the switch-arm cooperates, the said switch-arm being capable of moving from one lever to the other and adapted to hold the hammers in bent or to release them.

2. In a mechanism of the class set forth, the combination of a breech-locking bolt having an angular extension, a trigger-block carrying a slide having an inclined face and provided with a peg against which said extension bears and has a pushing operation, a trigger 115 having a switch-arm pivotally mounted thereon provided with a surface 38 adapted to receive pressure from the extremity of the slide opposite that carrying the peg, the switch-arm being horizontally disposed and having 120 a V-shaped part, and a spring having a V-shaped part co-operating with the similar part of the switch-arm.

3. In a mechanism of the class set forth, the combination with hammers, a trigger, a trig- 125

ger-block, and sear-levers, the trigger-block having slides with inclined ends, of a horizontally-disposed switch-arm pivotally carried by the trigger and having an angular member, a post forming part of the trigger, a spring secured to said post and having an angular surface coacting with the member of the switch-arm, the latter being horizontally disposed, and projections 44 with which the 10 inclined surfaces of the slides coöperate.

4. In a mechanism of the class set forth, the combination of a trigger means having a terminal projection 56, a horizontally-disposed switch-arm pivotally carried by the trigger 15 means and coöperating with the latter, sear-levers with which the switch-arm also coöp-

erates, a post 51, a block 52 slidably disposed about the post, the said block having a terminal shouldered portion adjacent to the projection 56 to engage the latter, means enabling 20 the said sliding block to engage under the trigger to obviate a second pull and also to engage over the trigger for safety, and a spring engaging the post and block.

In testimony whereof I have hereunto set 25 my hand in presence of two subscribing witnesses.

HARRY PRICE.
